Primary Examiner — David G Muller

(74) Attorney, Agent, or Firm — Withers Bergman, LLP;
Phillip Black(57) **CLAIM**

The ornamental design for a basin, as shown and described.

DESCRIPTION

FIG. 1 is a perspective view of the basin;

FIG. 2 is another perspective view thereof;

FIG. 3 is a top view thereof;

FIG. 4 is a front view thereof;

FIG. 5 is a back view thereof;

FIG. 6 is a side view thereof; and,

FIG. 7 is a bottom view thereof.

The contrast in shading represents a contrast in appearance
only and does not represent any particular color, material,
texture or finish.**1 Claim, 5 Drawing Sheets**FIG. 1
